UNITED STATES PATENT OFFICE.

PAUL AMADEO, OF SHENANDOAH, PENNSYLVANIA.

REGISTERING ATTACHMENT FOR BARBERS' CHAIRS.

1,101,981.

Specification of Letters Patent. Patented June 30, 1914.

Application filed September 17, 1912. Serial No. 720,720.

To all whom it may concern:

Be it known that I, PAUL AMADEO, a subject of the King of Italy, residing at Shenandoah, in the county of Schuylkill and 5 State of Pennsylvania, have invented certain new and useful Improvements in Registering Attachments for Barbers' Chairs, of which the following is a specification.

My invention relates to improvements in 10 registering attachments for barbers' chairs, the object of the invention being to provide a simple and efficient device which automatically registers in dollars and cents, shaves and hair-cuts.

15 A further object is to provide an improved register of this character in which the shaves are registered by the movement of the chair back and the hair-cuts by the raising and lowering of the chair seat.

20 A further object is to provide a register of this character which sounds a bell at every operation, and which is constructed to prevent fraudulent practices, enabling the proprietor and the barbers to keep an accurate account, and prevent any disputes as 25 to the work done.

With these and other objects in view, the invention consists in certain novel features of construction and combinations and arrangements of parts as will be more fully 30 hereinafter described and pointed out in the claims.

In the accompanying drawings: Figure 1 is a view in rear elevation of an ordinary 35 barber's chair illustrating my improvements connected thereto. Fig. 2 is a view in side elevation on an enlarged scale of my improved register detached. Fig. 3 is a view in front elevation of the same with the cover removed. Fig. 4 is a detail view in elevation 40 illustrating the bell and its sounding means. Fig. 5 is a view in vertical section through the casing illustrating the operating mechanism in elevation. Fig. 6 is a view in section on the line 6—6 of Fig. 5. Fig. 45 7 is a perspective view of one of the sliding bars 26, and Fig. 8 is a view in section on the line 8—8 of Fig. 5.

1 represents the supporting base of an 50 ordinary barber's chair provided with the hollow column 2 in which a plunger 3 is movable and supports the seat 4 of the chair.

5 is the back of the chair which is pivotally connected to the seat in any approved 55 manner, and I would have it understood that the details of construction of the chair

are immaterial as my invention is adapted for use in connection with any ordinary barber's chair, the one shown being for purposes of illustration only.

My improved register is provided with a casing 6 which is secured to the column 2 by means of straps 7, the attaching means being of course, immaterial. The casing 6 is divided by partitions 8 into two chambers 60 9 and 10 respectively, and in these chambers registering mechanisms are located, said registering mechanisms being precisely alike in construction and operation, and hence the description of one will apply alike to both.

My improved register is provided with a casing 6 which is secured to the column 2 by means of straps 7, the attaching means being of course, immaterial. The casing 6 is divided by partitions 8 into two chambers 60 9 and 10 respectively, and in these chambers registering mechanisms are located, said registering mechanisms being precisely alike in construction and operation, and hence the description of one will apply alike to both.

In each of the chambers 9 and 10, shafts 11 are mounted, and on these shafts 11 cylinders 12 are secured. These cylinders contain on their periphery, numerals indicating hair-cuts and shaves respectively. In other 70 words, one of these cylinders 12 is adapted to record in dollars and cents the hair-cuts and the other the shaves which are given to customers in the chair to which the register is connected.

The numerals, of course, will vary in accordance with the amount charged for shaves and hair-cuts, but the total amounts will be exposed through slots 13 in an angle plate 14 fixed in the front of the casing. This angle plate is normally closed by a hinged cover 15 having a suitable lock, the key 16 of which being shown in the lock, but which is normally removed and in the possession of the proprietor of the shop.

Gear wheels 17 are secured on the shafts 11 and mesh with pinions 18 on shafts 19. These pinions are engaged by the teeth of ratchet wheels 20 on the shafts 21 and the ratchet wheels 20 are held against accidental movement by pivoted pawls 22 which are held in engagement with the ratchet wheel by means of springs 23. These springs are connected at one end to the pawls and at their other ends to partitions 24 spaced from the rear wall of the casing and located in the upper portion thereof and constituting guides which limit the lateral movement of bars 26.

The bars 26, one of which is shown in Fig. 7, have recesses 25 to receive the teeth of ratchet wheels 20, so that when a bar is moved longitudinally it will cause the ratchet wheel to turn a distance of one tooth, such motion being transmitted through the pinion 18 to gear 17 and cylinder 12.

The upper end of the bar 26 which op-

erates the hair-cut register is connected by a link 27 with the chair bottom 4, while the bar 26 which operates the shave register is connected by a link 28 with the chair back 5. Hence, one of these bars is caused to move longitudinally by the raising and lowering of the chair which is always done when cutting hair, and the other bar is operated by the lowering and raising of the 10 chair back, which operation is always carried out when a customer is shaved.

The bars 26 have a certain amount of lateral movement toward and away from the ratchet wheels 20 to allow them to position themselves in operative engagement with the ratchet wheels when the bars are lowered and coiled springs 29 connect these bars with the shaft 19 and exert a normal downward pull upon the bars. The 15 springs have hooked ends so that they do not interfere with the turning movement of the shaft, and I would have it understood that if desired, these shafts may be stationary and the pinions turn thereon. The said 20 springs project through slots 30 in the partitions 24.

Laterally projecting arms 31 are secured to the bars 26, and project through the slots 30. These arms are provided with pivoted trips 32 which pivot only when the bar moves downward, and are held against pivotal movement when the bar moves upwardly. These trips 30 in their upward movement engage lugs 33 on pivoted arms 34. These arms 34 are connected by springs 35 with the shafts 19, and clappers 36 are secured to said arms and are adapted when the arms are moved downwardly by the springs to strike bells 37 to indicate that 35 the register has operated. It will thus be seen that when the bar 26 moves upwardly, it will cause the bell to be sounded, and this upward movement of the bar will cause the hair cut or shave cylinder 12 to turn, 40 as the case may be, and register the hair-cut or shave.

Various slight changes might be made in the general form and arrangement of parts described without departing from my 45 invention, and hence I do not limit myself to the precise details set forth, but con-

sider myself at liberty to make such changes and alterations as fairly fall within the spirit and scope of the appended claims.

Having thus described my invention, what 55 I claim as new and desire to secure by Letters Patent is:

1. A registering attachment for barbers' chairs comprising a casing divided into two chambers, a hair cut register in one chamber, a shave register in the other chamber, vertical partitions in said chambers spaced from the rear walls of the chambers, bars movable through the top of the casing and located between the partitions and the rear 60 walls of the casing, register operating toothed wheels in the chambers projecting into the spaces between the partition and the rear wall of the chamber, said bars having recesses therein to receive the teeth 65 of the toothed wheels, and springs normally pressing said bars against the partition and in operative engagement with the toothed wheels, substantially as described.

2. A registering attachment for barbers' 70 chairs comprising a casing divided into two chambers, a hair cut register in one chamber, a shave register in the other chamber, vertical partitions in said chambers spaced from the rear walls of the chambers, bars 75 movable through the top of the casing and located between the partitions and the rear walls of the casing, register operating toothed wheels in the chambers projecting into the spaces between the partition and the rear wall of the chamber, said bars having 80 recesses therein to receive the teeth of the toothed wheels, said partitions having openings therein, and springs projected through the openings in the partitions and 85 secured to the bars, said springs holding the bars normally against the partition, and adapted to return the bars to normal position when moved longitudinally, substantially as described.

In testimony whereof I have signed my name to this specification in the presence of two subscribing witnesses.

PAUL AMADEO.
